CLAIM

The ornamental design for a reflective safety belt, as shown and described.

DESCRIPTION

FIG. 1 is a front perspective view of the reflective safety belt showing my new design formed into a loop; FIG. 2 is a rear perspective view thereof; FIG. 3 is a top plan view in the unassembled state; and, FIG. 4 is a bottom view thereof.
The stippling on the striped portion of the belt represents a color contrasting surface.

FIG. 1

FIG. 2

FIG. 3

FIG. 4
